UNITED STATES PATENT OFFICE.

MANUEL DE ARRIGUNAGA, OF NEW YORK, N. Y.

STARTING APPARATUS FOR INTERNAL-COMBUSTION ENGINES.

1,283,103.

Specification of Letters Patent. Patented Oct. 29, 1918.

Continuation of application Serial No. 193,338, filed September 26, 1917, and division of application Serial No. 229,020, filed April 17, 1918. This application filed April 17, 1918. Serial No. 229,019.

To all whom it may concern:

Be it known that I, MANUEL DE ARRIGUNAGA, a citizen of the Republic of Mexico, formerly residing in Mérida, in the State 5 of Yucatan and Republic of Mexico, but now residing in the borough of Manhattan, in the city, county, and State of New York, have invented certain new and useful Improvements in Starting Apparatus for Internal-Combustion Engines of which the following is a specification.

My invention relates to starting apparatus for internal combustion engines, and the starting apparatus that is the subject 15 matter of the invention is particularly adapted to internal combustion engines of motor vehicles.

This application is a continuation of my co-pending application for starting apparatus for internal combustion engines, Serial No. 193,338, filed September 26, 1917, and a division of my co-pending application entitled Improvements in motor vehicles, filed on even date herewith. In the 25 last named application I have shown and described auxiliary steering apparatus for automobiles, with means for operating the same from the engine of the vehicle, means for controlling the operation of the same, 30 and a starting device with suitable connections between the same and the means for operating the auxiliary steering wheels; and in said application I have claimed said auxiliary steering wheels with the apparatus 35 for operating and controlling the same, and also the combination of a starting device and said auxiliary steering wheels with means whereby they may be selectively controlled. In this application I aim to 40 cover the starting device, connections between the same and the engine, and controlling mechanism therefor.

One of the objects of the invention herein claimed is to provide a durable and efficient 45 starting apparatus.

Another object of the invention is to provide a starting apparatus embodying a spring as the motive power so as to render the device simple and inexpensive to keep 50 in order.

Another object of the invention is to provide suitable means for controlling the operation of the same.

Further objects and advantages of the invention will more fully appear from the 55

following description taken in connection with the accompanying drawings illustrating the preferred embodiment of my invention.

My invention consists in the novel features of construction and combination of parts hereinafter more fully described and more particularly pointed out in the appended claims.

Referring to the drawings,

Figure 1 shows a front elevation of a part of the frame of the car with my invention in its preferred form applied thereto, with certain of the parts shown in section;

Fig. 2 is an enlarged front view of the 70 differential mechanism shown in Fig. 1, with certain parts in section;

Fig. 3 is an enlarged detail taken on line 3—3 of Fig. 2, showing means for controlling the starter, and with certain parts 75 broken away;

Fig. 4 is a plan view of certain parts of the control mechanism in the differential housing, for controlling the differential mechanism shown in Fig. 2;

Fig. 5 is a front view of the control means for controlling the starter;

Fig. 5^a is a central vertical sectional view of the same;

Fig. 6 is a view of the clutch mechanism 85 shown in the center of Fig. 1 with some of the parts omitted, the differential casing and mechanism being shown in section taken on line 6—6 of Fig. 1;

Fig. 6^a is a section taken on line a—a of 90 Fig. 6 showing a detail of the clutch controlling mechanism;

Fig. 7 shows an enlarged plan view, partly in section, of the starting apparatus shown at the upper right-hand corner of Fig. 1; 95

Fig. 8 shows a section of a part of the same, taken on line 8—8 of Fig. 7;

Fig. 9 shows auxiliary apparatus for starting the engine to be operated manually;

Fig. 10 shows details of part of the 100 starter; and

Fig. 11 is a view taken on line 11—11 of Fig. 7 showing manual means for storing up energy in the starter.

Referring to the drawings, a supporting 105 frame 45 (see Fig. 1) is bolted in any suitable manner, such as by bracket 46, to the side frame 47 of the chassis; and this supporting frame carries one end of a tubular supporting member 48, the other end of 110

which in turn fits within an annular socket 49 extending from the end of the differential housing 50. The opposite end of the differential casing has a similar socket 49' 5 into which fits one end of a tubular member 48' the outer end of which is carried in a supporting socket 51 secured to the opposite side piece 47' of the chassis by a suitable bracket 46'.

10 The differential shaft 30 extends through differential housing 50 and a housing 52 (containing a starting device hereinafter more fully described) supported by bracket 53 in any suitable manner from the side 15 piece 47'. The shaft within differential housing 50 is provided with two bevel gears 54, 54' mounted loosely on the shaft, and these gears mesh with the main differential or driving gear 55 mounted on the back of 20 the differential housing and adapted to be driven by or to drive the engine shaft in any suitable manner.

Referring again to Fig. 2, the hub of the differential gear 54 constitutes a clutch member 25 adapted to be engaged by a clutch member 62 carried by an annular frame keyed to the differential shaft 30 to slide back and forth thereon. This clutch member is provided with an annular groove 63 by means 30 of which the clutch member is forced back and forth along the key 64 to engage and disengage the hub of gear 54. A similar clutch device is keyed on the shaft 30 to engage and disengage the hub of gear 54' and 35 these clutch members are operated by the control mechanism hereinafter referred to, for clutching one or the other of the gears 54, 54' to the shaft 30, according to the desired direction of rotation of the shaft.

40 I will now describe the means for operating these clutch members by the control mechanism. The differential casing 50 is provided near each end and just below the said clutch members with transverse guide 45 rods 79, 79' (see Figs. 2 and 4). On the rods 79 there is slidingly mounted a cam member 80 having sleeves 81, 82 for slidingly fitting the guide rods so that the cam can be slid back and forth thereon. The guide rods 79' 50 at the opposite end of the casing are provided with a similar cam member 80' similarly mounted. The cam member 80 projects into the groove 63 of clutch member 62, and the cam member 80' has a similar projection extending into the groove 63' of 55 clutch member 62'. The cam members 80, 80' are connected, respectively, by downward 60 projections 83, 83' to an actuating link 84 having a short projection 85 extending through the floor of the housing and about the axis of which the link is swung to move the cam members back and forth on the guide rods for operating the clutch members 62, 62'. The actuating link is operated 65 by pull wires 86, 86' running to the dash,

where they are secured to control lever 87 (see Figs. 5 and 5^a). As shown, the wires 86, 86' are secured to the lever 87 in any well known manner, such for example as having the wires connected respectively to the peripheral portions of disks 88, 88' which are rotatably mounted on a short stub shaft 89 carried by a lever 90 secured to hub 91 of the lever 87. The lever 87 is made out of some suitable spring metal so that it is normally held up into a notch 92' in the flange of the guard 92, but when it is desired to move the lever, it is forced toward the dash 93 so as to free it from the flange of the guard 92, whereupon it may be moved in either direction. When brought back to the neutral position and released, the lever will spring back into the notch 92'. The numerals 94, 94' represent guides for the wires 86, 86' which latter may be inclosed in suitable flexible protecting sleeves, parts of which 95, 95' are shown in Fig. 5.

I will now describe mechanism which I preferably use for connecting and disconnecting the engine to the main differential gear 55, and the means for controlling the same. Referring to Fig. 6, it will be observed that the forward end of shaft 61 extends slidably through the main gear 55, which is suitably keyed to the shaft, and that the gear is held rotatably in position on the housing by the divided ring 59. It will also be understood that if desired, any suitable anti-friction bearing may be provided in place of this simple ring, which is shown for the sake of simplicity. The rear end of the shaft is provided with a clutch member 97 adapted to engage clutch 98 on the engine shaft 99. The clutch member 97 at the rear end of the shaft is adapted to slide back and forth through an upwardly extending bracket 100 carried by a horizontal supporting frame 101 suitably secured to the rear of the differential housing 50 (and reinforced if desired in any suitable manner). This frame 101 is also provided with an intermediate bracket 102 having an opening through which the shaft 61 slidably fits. The shaft has a collar 103 rigidly secured thereto, and between this collar and the bracket 102 there is provided a compression spring 104 tending to thrust the shaft forward to disconnect the clutch members 97, 98. The shaft is further provided with a second collar 105 rigidly secured to the shaft and having a lateral projection 106 for purposes herein-after mentioned. The shaft is also provided with threads 107 between this collar and the clutch member 97, and there is threaded on this portion of the shaft a nut 108 adapted to travel back and forth on the threads 107 as the shaft is rotated. The collar, nut and thread constitute a part of the means for automatically disconnecting the motor after the engine shaft has made a predetermined 125 130

number, say for example eight, revolutions. The nut 108 is provided with a depending lug 109 extending below the top of a locking plate or latch 110 secured to a shaft 111 suitably pivoted at each end in the main supporting frame 101. A coiled spring 112 tends to throw the plate in a vertical position. This plate extends upwardly toward the shaft 61 a sufficient height so that when 10 the shaft 61 is thrown backward to move clutch member 97 beyond the rear end of the latch plate, the latch plate, then in its upright position, extends above the lower edge of the clutch member so as to prevent the 15 spring 104 from moving shaft 61 forward to release the clutch members until the said latch or plate is tripped.

The following control apparatus is provided for forcing the shaft 61 rearward to 20 engage the clutch members 97, 98: Referring to Fig. 4, it will be observed that there is also provided in the differential housing just above the actuating link 84, a member 113 the arms of which are provided with 25 sleeves 114, 114' adapted to slide along the inner guide rods 79, 79' so that the member 113 may be moved across the differential housing guided on said rods. The sleeves 114, 114' are adapted to be engaged by the 30 inner ends of the sleeves 81, 81' secured to the cam members 80, 80', so that if either cam member is moved toward the rear of the casing by its pull wire, one or the other of the sleeves 114, 114' is engaged, thus 35 causing the slide member 113 to be moved rearwardly with the said cam member. This slide member 113 is provided with an upwardly and forwardly extending bracket 115 (see Figs. 4 and 6) having a centering 40 pin 116 carried at its upper end adapted to fit into the bored-out forward end of the shaft 61 when the slide member 113 is moved to the rear of the casing. By this mechanism whenever one of the pull wires 86 or 45 86' is operated to move one of the cam members 80 or 80', the slide member 113 is moved rearwardly of the casing 50, and as the upper end of the bracket 115 engages the forward end of shaft 61, it forces the shaft 50 rearwardly against the compression of spring 104, engaging clutch members 97, 98 to clutch the shaft to the engine. The construction and movement of the slide member 113 and of the cam members 80, 80' are 55 preferably such that the cam member operates to clutch the differential bevel to the differential shaft before the shaft 61 is thrust rearwardly sufficiently to close the clutch 97-98 to the engine shaft for rotating the differential shaft.

In order to reverse the rotation of shaft 61 after the engine has been unclutched the coiled spring 117 is secured at one end to the hub of the main bevel gear 55, and at 65 its other end to the housing 50. When the

operator pulls lever 87 to the left, he pulls on wire 86 thus drawing cam member 80 to the rear of the differential casing, which in turn closes the clutch 62, for connecting bevel gear 54 to the differential shaft. The 70 pull on wire 86 also causes the sliding frame 113 to move rearwardly, thus thrusting the clutch shaft 61 (see Fig. 6) rearwardly against spring 104 to close clutch 97-98 to the engine, whereupon the differential shaft 75 is driven from the engine against the direction indicated. The minute that the clutch members 97-98 become engaged to cause clutch shaft 61 to rotate, the nut 108 being held from rotation by engagement of its depending portion 109 with the latch 110, immediately commences to travel forward on the threads 107. When the shaft 61 has made a certain number of revolutions, for example eight, the said traveling nut 108 is 80 brought up against collar 105, whereupon lateral projection 106 from said collar engages projection 108' from the nut and thereby knocks it around, causing the projection 109 of the nut to strike the locking plate 110 85 and swing it on its axis down against spring 112 until it clears the lower end of the clutch member 97, whereupon spring 104 immediately thrusts the shaft 61 forward into the position shown in Fig. 6, thereby unclutching 90 the engine from the differential shaft. The forward movement of shaft 61 also thrusts slide member 113 forward in the differential housing, thereby forcing the said cam member 80 and actuating lever 84 to 95 their neutral positions; the movement of lever 84 also forcing the control lever 87 to its neutral position. As soon as the sliding cam member 80 is thus thrown to its neutral position, it opens the differential gear 100 clutch 62, whereupon the coiled spring 117 about the hub of the main differential gear 55 rotates said gear in the reverse direction to that in which it is driven by the engine, whereupon the threaded nut 108 travels 105 backward on threads 107 until it again reaches the position shown in Fig. 6, which arrests the rotation of shaft 61, and the clutch shaft and mechanism are again in position to be operated to be clutched to the 110 engine shaft and to be automatically released therefrom after a predetermined number of revolutions. It will be seen that the coil spring 117 is automatically wound up when clutch 97-98 is closed.

When lever 87 is swung to the right, it 115 pulls on wire 86' to throw the cam member 80' and also the slide member 113 to the rear of the casing, thus closing clutch 62' and closing engine shaft clutch 97-98, whereupon the engine drives the differential shaft 120 in the opposite direction. After the predetermined number of rotations of the shaft 61, nut 108 will have traveled forward to engage projection 106 to again release the 125 130

latch 110 for opening the engine clutch and for forcing the clutch shaft 61 forward to move the control lever 87 to its neutral position, whereupon the clutch 62' is also opened. Referring to Figs. 1 and 7, the supporting housing 52 carried by side frame 47, is provided at the sides with supporting bearings for the differential shaft 30; and extending horizontally from said housing there is a cylindrical casing 122 the end of which adjacent the housing is fitted over an annular flange 123 extending from the housing. The casing 122 is provided at its rear end with grooves or guideways 124, and within the casing there is provided a slide block 125 carrying a series of pulleys 126. Rollers 127 are mounted between the slide block and the casing to run in said grooves, so that the block may be guided back and forth in the casing. The housing adjacent the casing is provided with a stub shaft 128 secured to the housing by being passed through bores in the upwardly extending flange 123, and on this shaft are rotatably mounted a series of individual rotatable wheels or pulleys 129. Between the slide block 125 and the upper end of the flange 123 there is provided a relatively powerful compression spring 130 which exerts its force against the slide block 125 to move the same rearwardly in the casing 122. The slide block is normally held against the compression of this spring by a suitable wire or rope 132 secured to the slide block and passing successively over one of the pulleys 129 on the shaft and over one of the pulleys 126 on the slide block, and finally passing between two guide rollers 133 secured to the housing, and from thence onto the drum 134 onto which it is wound and its end secured. This drum, as shown in Fig. 10, is rotatably mounted upon a sleeve 135 which in turn is keyed to the differential shaft 30 so as to rotate therewith, and free to slide back and forth thereon, and the drum is held from sliding off the sleeve by any suitable means such as a pin 136 carried by the drum 134 and co-acting with a circumferential groove 136' in the sleeve 135, so that the drum and sleeve may slide back and forth along shaft 30 during the winding of the rope on the drum when the spring is being compressed, and the unwinding of the rope from the drum when the spring is extending. The drum is provided with a flange 137 having a projection 138 upon which is pivotally mounted a dog 139 the nose of which is held pressed inwardly by spring 140 against shoulder 141 cut in the flange of the sleeve 135 so as to hold these two normally locked together from relative rotation. The housing is provided at its right-hand end with an inner projection 142 (see Fig. 8), so located that when the drum 134 is moved to its extreme position to the right (at which the spring

would have been coiled to its desired extent), the projection will be in the path of rotation of the dog so as to strike the tail of the same to release the nose of the dog from the shoulder 141 and thus unlock the drum and sleeve to prevent overwinding of the spring, as hereinafter described.

Without considering for the present the mechanism for governing the starting device and its connection to the engine, it will be seen that with the spring compressed as shown in Fig. 7, if suitable means be provided for locking shaft 30, but for releasing the same when it is desired to start the engine, the extension of spring 130 will pull on the drum 134 which, being locked to the sleeve 135 by the dog 139, which sleeve is in turn keyed to shaft 30, will cause the shaft to rotate in the direction of the arrow shown in Fig. 7 to drive shaft 30 which, when clutch 62' is closed by the control mechanism heretofore described, will cause the engine to be turned over to start the same. During this movement the drum will move toward the left from the position shown in Fig. 7. It will be furthermore understood that when the engine is rotating the shaft 30 against the direction shown by the arrow in Fig. 7 this movement will rotate drum 134 to compress spring 130, during which movement drum 134 is moved toward the position shown in Fig. 7; and if the rotation of shaft 30 should continue after the spring has been compressed to the desired extent, the drum 134 will be in the position shown in Fig. 7; and if the rotation is continued, the tail of dog 139 will strike projection 142, releasing the nose of the dog from shoulder 141, thereby allowing the spring to momentarily rotate the drum 134 in the direction shown by the outer arrow in Fig. 8, during which time the continued rotation of shaft 30 rotates sleeve 135 in the opposite direction. As a result of this, after the drum and sleeve have been rotated in opposite directions each for a part of a revolution, the nose of the dog will again engage shoulder 141 to lock the sleeve and drum together; but if at this time shaft 30 is continuing to rotate, the tail of dog 139 will again be brought into engagement with projection 142, which will cause the drum and sleeve to be again released, and so on as long as shaft 30 continues to rotate after the spring has been completely compressed.

I will now describe the locking device for shaft 30 and the means for releasing the same when it is desired to start the engine from the starter. Referring to Figs. 2 and 3, it will be seen that within the differential housing 50 a gear 145 is keyed to shaft 30, and this gear meshes with gear 146 keyed to shaft 147 journaled on an upright frame or bracket 148 extending up from the floor of the said housing. These two gears are

desirably chosen with the ratio of 1 to $\frac{1}{2}$, because the differential gears 55, 54' are chosen with the ratio of $\frac{1}{2}$ to 1, the object being that for every complete revolution of 5 the engine shaft, the shaft 147 carrying gear 146 will make one complete revolution. Normally gear 146 and hence shaft 30 are held from rotation by a latch 149 adapted to engage ratchet shoulder 150 formed on 10 member 150' secured to shaft 147. The latch is hung or swiveled on a pin 152 carried by a bracket 153 from the upper part of the differential housing. Spring 155 forces the latch toward shaft 147, in position to be engaged by shoulder 150. The shaft 147 has also secured thereto a substantially radial arm 151 adapted to engage pin 154 on lever 84 to force lever 84 and the parts movable therewith to neutral position after a predetermined amount of rotation of shaft 30 by 20 the starter, as hereinafter more fully explained.

When it is desired to start the engine, the operator swings lever 87 (see Fig. 5) to the right to pull wire 86', the pulling of this wire will rock actuating link 84 on its pivot 85 to move the cam member 80' and sliding member 113 as heretofore described, for closing the engine shaft clutch 97-98 and also 30 clutch 62' to connect gear 54' to the differential shaft; but the swinging of link 84 also causes the left-hand end thereof to swing forward in the differential housing, thereby bringing projection 84' thereon (see 35 Figs. 3 and 4) into engagement with the lower end of latch 149 so as to release the latch from ratchet shoulder 150, and gear 146 is then free to be rotated under the power of the starter to turn over the engine 40 shaft until arm 151 engages projection 154 and moves lever 84 back to its neutral position whereby the clutch 62' is reopened permitting the engine to operate independently of the starter and whereby also the lever 87 45 is moved back to its central position. Further rotation of shaft 147 brings ratchet shoulder 150 into engagement with the latch shoulder, spring 155 being sufficiently strong to move the latch into engagement with the 50 member 150' but not to move lever 84 and its connected parts back to neutral position. In view of the ratio of the gearing as above mentioned, the engine shaft will, during the same time, have made substantially one complete revolution. If this is not sufficient to start the engine, the operator moves lever 87 back to the right to cause projection 84' to again release latch 149, whereupon the engine is driven by the starter through substantially a second revolution. This operation 60 may be repeated as many times as may be necessary to start the engine.

The spring 130 may be compressed by the engine by moving the lever 87 (Fig. 5) to the left thereby pulling on wire 86 and

causing cam 80 to close clutch 62 and clutch 97-98, whereupon the shaft 30 is rotated by the engine in a direction opposite that indicated by the arrows in Figs. 2 and 7, thereby causing the spring 130 to be compressed. Upon the automatic opening of the clutch 97-98, as explained, the lever 87 is automatically moved back again to its central or neutral position. Over-compression of the spring 130 is, as heretofore explained, avoided by the ratchet connection and release mechanism described in connection with the drum 134.

If at any time it is desired to compress the spring manually, this is accomplished 80 by ratchet-wheel 165 (see Figs. 7 and 11), keyed to shaft 30 at the inner end of the casing 52, which ratchet-wheel may be rotated by a lever 166 rotatably mounted on shaft 30 and carrying a pivoted pawl 166' 85 arranged to co-act with the teeth of the ratchet-wheel 165. A detent pawl 166'', which may be pivoted to the housing 52 and is arranged to co-act with the teeth of the ratchet-wheel 165, is provided to prevent rotation of the shaft 30 by the spring 130 during the operation of the lever 166. When the spring is sufficiently wound, the detent-pawl 166'' and the pawl 166' are moved out of operative position with respect to the 90 teeth of the ratchet-wheel 165, the shaft 30 being normally held against rotation by the engagement of the latch 149 with the ratchet-shoulder 150.

I have also provided means for starting 100 the car motor from the seat of the vehicle in the event that for any reason the starting device described should be broken or otherwise get out of order. This device consists of a ratchet 168 mounted at the right-hand 105 end of shaft 30 (see Figs. 7 and 9). Adjacent this ratchet wheel an operating lever 169 is swiveled on the end of shaft 30 by means of a sleeve 170 fitting over the shaft. This lever carries a sliding ratchet bolt 171 110 guided by suitable guides 172 on the lever 169, and between one of these guides 172 and a collar 173 secured to the bolt, there is provided a compression spring 174 for moving the bolt out of engagement with the ratchet-wheel 168. The upward throw of the bolt is limited by a second collar 175. The lever 169 is normally held in the position shown in Fig. 9 by a coiled spring 176 connected at one end to the lower end of the lever and at 115 the other end to a bracket 177 on casing 122. To the upper end of the lever there is pivoted a bell crank lever 178 one end of which is adapted to rest against the head of the bolt 171, and to the other end of this bell crank lever is secured a wire 179 running to the dash, so that when the operator pulls on this wire he holds the bolt firmly in engagement with the ratchet and moves the lever 120 in a direction to turn the ratchet and shaft 130

30 through a part of a revolution to start the engine. If it does not start on the first movement of the lever, the operator releases wire 179, thus permitting the spring 176 to 5 throw the lever forward, whereupon if wire 179 is again pulled, the shaft 30 is moved through another part of a revolution, and so on until the engine is started.

It will also be obvious to those skilled in 10 the art, after having understood my invention, that various changes and modifications may be made therein without departing from the spirit or scope of the invention, and I aim in the appended claims to cover 15 all such modifications.

Having thus described my invention, what I claim as new and desire to secure by Letters Patent, is:—

1. In apparatus for starting internal combustion engines, the combination of energy 20 storing means having sufficient capacity and extent of movement with a single supply of energy therein to impart a plurality of starting impulses to the engine, a movable member operatively connected to said means, 25 means for holding said movable member against movement, means for rendering said holding means inoperative and for thereafter automatically rendering the same 30 operative after a predetermined part only of the total storable energy in said first named means has been expended, a second movable member, means for connecting said second movable member to said first named movable 35 member to cause said members to move either in the same direction or in opposite directions, means connecting the second movable member with the engine, and automatic means for rendering said last named connecting means inoperative.

2. In apparatus for starting internal combustion engines, the combination of a spring having sufficient capacity and extent of movement with a single supply of energy 45 therein to impart a plurality of starting impulses to the engine, a shaft operatively connected to said spring, means for normally holding said shaft against rotation, means for rendering said holding means inoperative 50 and for thereafter automatically rendering the same operative after a predetermined part only of the total storable energy in said spring has been expended, a second shaft, means for connecting said shafts to 55 move in the same or opposite directions, means for connecting said second shaft with the engine and automatic means for rendering said last named connecting means inoperative.

60 3. In apparatus for starting internal combustion engines, the combination of a spring having sufficient capacity and extent of movement with a single supply of energy therein to impart a plurality of starting 65 impulses to the engine, a support for the

spring at one end thereof, means at the other end of the spring operated thereby, a guide for said means, a rotatable member, means connecting the spring-operated means with the rotatable member to rotate the latter, 70 means for connecting the rotatable member with the engine to rotate the engine and for disconnecting the same, means for normally holding the rotatable member from rotation, and means for rendering said holding means 75 inoperative and for thereafter automatically rendering the same operative, after a predetermined part only of the energy storable in said spring has been expended.

4. In apparatus for starting internal combustion engines, the combination of a compression spring having sufficient capacity and extent of movement with a single supply of energy therein to impart a plurality of starting impulses to the engine, a support 80 for the spring at one end thereof, a traveler at the other end of the spring operated thereby, guide means for said traveler, a rotatable drum, means including a cord and pulleys for connecting said traveler and drum to rotate the drum when the traveler is operated, means including a clutch for connecting and disconnecting the drum and engine, means for normally holding the drum from rotation, and means for rendering said holding means inoperative and for thereafter automatically rendering the same 85 operative after a predetermined part only of the energy storable in said spring has been 90 expended.

5. In apparatus for starting internal combustion engines, the combination of a compression spring having sufficient capacity and extent of movement with a single supply of energy therein to impart a plurality of 105 starting impulses to the engine, a support for the spring at one end, a traveler at the other end of the spring driven by the spring, pulley wheels mounted on said traveler, and other pulley wheels stationary with respect 110 to the traveler, a rotatable drum, a cord passing over said pulley wheels and connecting said traveler and drum, means including one or more clutches for connecting and disconnecting the engine and drum, means for normally holding the drum from rotation, and means for rendering said holding means 115 inoperative and for thereafter automatically rendering the same operative after a predetermined part only of the energy storable in 120 said spring has been expanded.

6. In apparatus for starting internal combustion engines, the combination of a shaft, a drum mounted on the shaft to rotate therewith, a supporting frame, a compression 125 spring the thrust of one end of which is taken by said frame, a housing for the spring extending from said frame, a traveler in the other end of the housing against which the spring thrusts to move the same, guides in 130

- the housing for the traveler, pulley wheels mounted on the traveler, other pulley wheels mounted on the frame, a cord connecting said drum and traveler and passing over the 5 pulley wheels, differential gearing on the shaft, clutch means for causing the engine to be operatively connected with said shaft, and means normally locking said shaft from operation.
- 10 7. In apparatus for starting internal combustion engines, the combination of a shaft, a drum rotatable with the shaft, means connecting said drum to the shaft including a sleeve keyed to the shaft and a pivoted 15 ratchet dog connecting said sleeve and drum, a supporting frame, a compression spring the thrust of one end of which is taken by said frame, a housing for the spring extending from said frame, a traveler in the other 20 end of the housing against which the spring thrusts to move the traveler, guides in the housing for the traveler, pulley wheels mounted on the traveler, other pulley wheels mounted on the frame, a cord connecting 25 said drum and traveler and passing over the pulley wheels, a trip for releasing the ratchet dog when the drum has been rotated to compress the spring a predetermined amount, means normally locking the drum and shaft 30 from rotation, means including clutches for connecting the shaft and engine, and control means for the clutches and said locking means.
8. In apparatus for starting internal combustion engines, the combination of a spring, a rotatable member connected to the spring to be rotated thereby, means including a clutch for operatively connecting the rotatable member and engine, means for automatically releasing the clutch after the engine has made a movement of predetermined amount, means including a plurality of clutches for causing the rotatable member to move in opposite directions without a reversal of the engine, means for normally holding the rotatable member from operation, and control means for operating the clutches and releasing the rotatable member.
9. In apparatus for starting internal combustion engines, the combination of a compression spring, a support for the spring at one end, a traveler at the other end of the spring driven by the spring, pulley wheels mounted on said traveler, and other pulley 55 wheels stationary with respect to the traveler, a rotatable drum, a cord passing over said pulley wheels and connecting said traveler and drum, means including a clutch for operatively connecting the drum and engine, 60 means for automatically releasing the clutch after the engine has made a movement of predetermined amount, means for normally holding the drum from operation, and control means for closing the clutch and releasing the drum.
10. In apparatus for starting internal combustion engines of motor vehicles, the combination of a spring, a rotatable shaft, means connecting said shaft and spring to rotate the shaft by the spring, differential 70 gearing and clutches for connecting said shaft with the engine, a housing for the gearing and clutches, means in the housing for normally locking the shaft against rotation, control mechanism in the housing for 75 operating the differential gear clutches, and means on the dash of the vehicle connected with said control mechanism for operating the clutches and releasing the locking means.
11. In apparatus for starting internal combustion engines of motor vehicles, the combination of a compression spring, a support for the spring at one end, a traveler at the other end of the spring driven by the spring, pulley wheels mounted on said traveler, and other pulley wheels stationary with respect to the traveler, a rotatable drum, a cord passing over said pulley wheels and connecting said traveler and drum, means including a clutch for operatively connecting 80 the drum and engine, means for automatically releasing the clutch after the engine has made a movement of predetermined amount, means for normally holding the drum from 85 operation, and control means operated from 90 the dash of the vehicle for releasing the drum for a movement of predetermined amount only.
12. In apparatus for starting internal combustion engines, the combination of a spring, a rotatable shaft, means connecting said shaft and spring to rotate the shaft by the spring, means for driving the engine from said shaft or said shaft from the engine including differential gearing comprising 100 two differential gears loosely mounted on said shaft, a gear meshing therewith and connected with the engine, and differential clutches for connecting the first-mentioned differential gears to the shaft to rotate therewith, locking means for normally holding said shaft against rotation, and control mechanism for operating said clutches and releasing the locking mechanism.
13. In apparatus for starting internal combustion engines, the combination of a compression spring, a support for the spring at one end, a traveler at the other end of the spring driven by the spring, pulley wheels mounted on said traveler, and other pulley 105 wheels stationary with respect to the traveler, a rotatable drum, a cord passing over said pulley wheels and connecting said traveler and drum, a rotatable shaft, means connecting said shaft and drum for rotating either of said parts when the other is rotated, means for driving the engine from said shaft or said shaft from the engine including differential gearing comprising two 110 differential gears loosely mounted on said 115 shaft.

shaft, a gear meshing therewith and connected with the engine, and differential clutches for connecting the two differential gears to the shaft to rotate therewith, locking means for normally holding said shaft against rotation, and control mechanism for operating said clutches and releasing the locking mechanism.

14. In apparatus for starting internal combustion engines, the combination of a compression spring, a support for the spring at one end, a traveler at the other end of the spring driven by the spring, pulley wheels mounted on said traveler, and other pulley wheels stationary with respect to the traveler, a rotatable drum, a cord passing over said pulley wheels and connecting said traveler and drum, a rotatable shaft, means connecting said shaft and drum for rotating the shaft when the drum is rotated, means for driving the engine from said shaft or said shaft from the engine including differential gearing comprising two differential gears loosely mounted on said shaft, a main gear meshing therewith for driving the engine, and differential clutches for connecting the two differential gears to the shaft to rotate therewith, locking means for normally

holding said shaft against rotation, control mechanism for operating said clutches and releasing the locking mechanism, and means preventing excessive compression of the spring.

15. In apparatus for starting internal combustion engines, the combination of a spring having sufficient capacity and extent of movement with a single supply of energy therein to impart a plurality of starting impulses to the engine, a shaft operatively connected to said spring, means for normally holding said shaft against rotation, means for rendering said holding means inoperative and for thereafter automatically rendering the same operative after a predetermined part only of the total storable energy in said spring has been expended, a second shaft, means for connecting said shafts to move in the same or opposite directions, means for connecting said second shaft with the engine, automatic means for rendering said last connecting means inoperative, and means for rotating said first named shaft manually.

In testimony whereof, I have signed my name to this specification.

MANUEL DE ARRIGUNAGA.
